UNITED STATES PATENT OFFICE.

EDMUND W. MOORE, OF ROCHESTER, NEW YORK, ASSIGNOR TO GENERAL RAILWAY SIGNAL COMPANY, OF GATES, NEW YORK, A CORPORATION OF NEW YORK.

MOUNTING FOR INCANDESCENT LAMPS OF RAILWAY LIGHT SIGNALS.

Application filed September 30, 1921. Serial No. 504,456.

To all whom it may concern:

Be it known that I, EDMUND W. MOORE, a citizen of the United States, residing at Rochester, in the county of Monroe and

- 5 State of New York, have invented certain new and useful Improvements in Mountings for Incandescent Lamps of Railway Light Signals, of which the following is a specification.
- 10 This invention relates to the structure of a mounting or support for electric lamps used in light projecting systems, and more particularly to the mounting for concentrated filament lamps employed in light signals for railway signaling purposes.

In order to obtain visibility of signals for a long range and through a considerable angle of spread, during the day time as well as at night, and to maintain a desirable low energy consumption, an efficient light projecting unit is required. To accomplish these ends, besides well designed optical devices or light concentrating devices, such as reflectors, lenses, etc., it is necessary to have a concentrated light source properly located with respect to such optical devices. If the concentrated light source is an incandescent lamp which must be renewed from time to time, it is desirable to be able to make such replacements in the field conveniently, and at the same time have the replaced filament assume the same and proper relation with respect to the optical devices as that of the lamp replaced. Lamps manufactured in quantities on a commercial scale, however, do not have their filaments in any definite relation with respect to their bases, and consequently when lamps of this kind are used in connection with light concentrating devices and burn out, or are otherwise unfit for service and must be replaced, adjustments to properly focus them are required. Such adjustments of lamps in the field are a cumbersome and an expensive expedient, since at least two experienced workmen are required, one at the signal to change the adjustment, and the other at a distance to determine from the appearance of the signal when the proper adjustment has been made.

With the idea of obviating the necessity of this procedure each and every time a new lamp is placed in service, it is proposed in the present invention to fix up or rebase

55 commercial lamps in such a way, that their

respective filaments will be accurately located with respect to the optical device in which they are to be used when the lamps are placed in service.

On account of the importance of having 60 the filament of the various lamps placed in a signal to come at the same and proper point, it is necessary to provide a suitable mounting for the lamp which will permit it to be quickly and easily detached and 65 which will positively position the same. In order to accomplish these ends, it is further proposed in accordance with the present invention to employ a bayonet type socket, and to provide lamps of commercial manufacture with an auxiliary or supplemental base adapted to fit such sockets in such a way as to positively position the filaments of these lamps, regardless of reasonable variation of the size of parts incident to 70 commercial manufacture, and likewise permitting quick and easy detachment. More specifically a concentrated filament lamp of commercial manufacture is provided with a supplemental sleeve over its cylindrical base 75 having three pins corresponding to bayonet slots in a socket shell in which it is to be supported. Cooperation of the three pins with the hook shaped slots of the base results in 80 a three-point support, thereby positioning the direction of the axis of the lamp regardless of the snugness of fit of the auxiliary base in the socket.

Other objects and purposes of the invention will appear as the description progresses, and the novel features thereof will be pointed out in the appended claims.

In describing the invention in detail, reference will be made to the accompanying drawings, in which:

Fig. 1 shows a concentrated filament lamp illustrated as having one assumed commercial inaccuracy in the location of its filament;

Fig. 2 shows one form of supplemental base embodied in the present invention;

Fig. 3 illustrates another form of supplemental base;

Fig. 4 shows the supplemental base illustrated in Fig. 3 applied to the lamp illustrated in Fig. 1; and

Fig. 5 shows a light projecting unit and the rebased lamp contained therein, both of which are constructed in accordance with the present invention.

One specific form of light projecting unit has been illustrated in Fig. 5 to explain the importance of having the filament of a lamp properly located with respect to its base, and 5 consequently with respect to an optical unit, such as a lens. A portion of a casing 1 is shown having a circular opening provided with a lens seat, in which rests a lens 2. This lens is held in place by a retaining ring 10 3 secured to the casing by screws 4, and extending considerably below the lens 2. A gasket of felt or similar material is preferably interposed between the edge of the lens and the casing 1, but the retaining ring 3 15 bears directly against the lens. To this retaining ring 3 an angle bracket 5 is fastened by bolts 6, and on this bracket is fixedly supported a lamp receptacle consisting of a porcelain base 7 and a socket shell 8, provided with a plurality of bayonet slots of the usual shape forming hooks. This socket shell 8 is held firmly against the porcelain base 7 by the plate 11 and screws 12. In the center of the base is a metallic socket member 13, in which is slidably mounted a plunger 14, which is resiliently held upward by a helical spring 15. The head of the plunger 14 is held within the socket member 13 by a conducting plate 16, which 20 is held in place by a screw 17. Both the plates 11 and 16 are provided with a binding post 18 which serve to conduct current to the plunger 14 and socket shell 8 respectively. In the manufacture of these 25 light projecting units, the socket shell 8 and its slots are definitely located with respect to the lens 2 by a standard jig or fixture used during their assemblage.

In Fig. 1 there is shown one typical form 40 of incandescent lamp adapted to be used in connection with the present invention. Such lamps when manufactured on a large scale commercially, frequently have their filaments inaccurately located with respect to the bases of the lamps, and in the lamp shown it is assumed for the purpose of explanation that the stem supporting the filament is tipped to one side of the axis of the base. In the particular form of lamp 45 illustrated, the filament comprises two parallel convoluted filaments 19, both attached to the usual lead-in wires so that both filaments are normally lighted, one serving as a reserve when the other burns out. The lamp 50 is provided with a plain cylindrical base 20 of the single contact type without threads or pins. Since it is desirable to use lamps interchangeably in a light projecting unit, such as illustrated in Fig. 5, and in each instance have the concentrated filament of the 55 lamp come at the proper point with respect to the lens or other optical device of said unit; and since lamps of commercial manufacture do not have their filaments accurately located with respect to their regular

bases, as illustrated in Fig. 1, it becomes apparent that commercial lamps should be fixed up in some suitable way so that their filaments, regardless of irregularities in their location with respect to the regular bases 70 of the lamps occurring during commercial manufacture, will have a predetermined and definite relation to the socket in which the lamp is placed.

It is proposed in this invention that an 75 auxiliary or supplemental base be attached to the usual base of commercial lamps in a manner to bring the filament in a definite relation to the supplemental base. The specific supplemental base embodying the 80 present invention comprises a metallic sleeve 21 having an outside diameter to snugly fit the socket shell of the receptacle, leaving just sufficient clearance to allow for commercial inaccuracies in manufacture, and having its 85 internal diameter sufficiently larger than the cylindrical base of a commercial incandescent lamp, to permit it to be tiltably adjusted within the sleeve far enough to take care of ordinary inaccuracies in the location 90 of the filament. In this sleeve are holes in which are riveted, soldered, or otherwise suitably fastened short radially projecting pins 22, these pins being adapted to fit in the bayonet slots of the socket shell 8. In 95 practice the sleeve 21 is properly attached to the base 20 of the commercial lamp by placing the sleeve 21 and lamp in a fixture, properly positioning the lamp filament 19 with respect to the sleeve 21, and then 100 soldering the sleeve and lamp base together at two or more points, as illustrated at 105 23 in Figs. 4 and 5.

After a standardized lamp has been provided in the manner above described, it is 110 also important to provide a supporting structure for the lamp which will prevent tilting or sidewise displacement, in order that the filament will always be in the proper position, although the lamp may be 115 carelessly tipped when inserted, or subjected to jar and vibration. With the usual bayonet type socket and base having two pins affording a two-point support, on account of the loose fit between the rebasing 120 sleeve 21 and the socket shell 8 required for commercial manufacture, it is evident that the lamp may tilt or rock about the pivot axis formed by the two pins; and while this movement may be relatively small at the base of the lamp, it is multiplied at the filament, and may result in displacement of the filament from its proper position to an extent seriously interfering with the efficiency 125 of a light projecting unit. In order to oppose this tilting movement of the lamp, the rebasing sleeve 21 in accordance with this invention is provided with resilient means disposed or effective at points between the 130 two pins 22. In the particular construction

shown, two pairs of slots are cut in the rebasing sleeve 21 partway down from the upper edge, leaving tongues 24 or fingers which are forced or bent outward, preferably in 5 the shape shown in Fig. 2, so that the upper portion of these tongues is substantially parallel with the surface of the sleeve 21. The rebasing sleeve 21 is made of brass, or other suitable material, so that these tongues 24 10 have the desired resiliency and stiffness. The tongues are formed in the rebasing sleeve 21 before the lamp is adjusted and soldered therein, the adjustment of the lamp in the sleeve taking care of any slight variations that might exist in the shape or stiffness of said tongues. When the rebased lamp is inserted in the socket shell 8, the 15 spring tongues 24 engage this shell and hold the lamp in the proper position. These 20 spring tongues 24 not only straighten up the rebasing sleeve 21 in the socket 8, so that no special care is required in putting in a lamp, but also resist any tendency of the lamp to tilt out of the proper position, due 25 to shock, vibration, or other causes.

These resilient tongues are formed on the rebasing sleeve 21, rather than on the socket shell 8, because the lamp may be adjusted while the rebasing sleeve 21 is being applied 30 to take care of any irregularities in these tongues 24; whereas, if the tongues 24 were formed on the socket 8, any irregularities therein would affect the position of all lamps put in that socket, and compensation for 35 such irregularities would be a matter of considerable difficulty. Further, in case these tongues 24 are accidentally or carelessly bent out of shape, or broken off, the injury would, if the tongues 24 were on the sleeve 21, only affect the lamp in question, which could be discarded and another used in its place; whereas, if the tongues 24 were on the 40 socket shell 8, the injury would be permanent and would have to be remedied before 45 the signal could be used. Likewise, if the spring tongues 24 were formed on the socket shell 8, these tongues 24 would be subjected to bending and distortion each time a new lamp is inserted, and in short, would have 50 to stand up for the life of several lamps; whereas, the tongues 24 on the rebasing sleeve 21 are subjected to only one distortion when that particular lamp is put into service 55 and need last no longer than the life of one lamp.

Obviously, equivalent resilient projections may be formed or attached to the sleeve in a way different from that shown and described, and the particular form of the 60 spring tongues shown is merely illustrative of the invention.

In order to determine positively the direction of the axis of the lamp when its rebasing sleeve 21 is inserted in a socket, and to 65 prevent positively any tilting of the lamp,

three radially extending pins 22¹ may be provided on the rebasing sleeve 21¹, as shown in Fig. 3. By this arrangement a three-point support is provided, thus supporting the rebasing sleeve 21¹ in a definite 75 plane, thereby positively determining the direction of the axis of the sleeve 21¹ with respect to the socket shell 8. Although by this arrangement no tilting of the lamp in the socket 8 is possible, sidewise movement 75 of the sleeve 21¹ with respect to the socket 8 is still possible to the extent of the clearance between the sleeve 21¹ and socket 8; and if desired, three spring tongues 24¹ disposed at 80 points between the pins 22¹, may be formed 80 in the sleeve, as shown in Fig. 3, in the same way as illustrated in Fig. 2. Since this sidewise movement is under ordinary conditions very small, the tongues 24¹ illustrated in Fig. 3 may be omitted. 85

In lamp mountings of this kind, it is important that the flat side of the filament should face the optical device, such as the lens 2 in each instance. When a two-pin rebasing sleeve 21 is employed having its pins 22 diametrically opposite, one or the other of the flat faces of the filament 19 will face the optical device depending on how the lamp is inserted, which, although not an ideal construction, is satisfactory; but a more precise arrangement may be provided, if desired, by disposing the two pins 22 unsymmetrically about the sleeve 21, thereby permitting the lamp to be inserted in one particular way only, that is, with the same side of the filament facing the optical unit as was determined when the rebasing sleeve 21 was applied. In order to permit the lamp provided with a sleeve 21¹ having three pins 22¹ to be placed into a socket in one definite relation only, it is desirable to have the pins 22¹ unequally spaced about the circumference of the base, as shown in Figs. 3 and 5 of the drawings, where two of the pins 22¹ are spaced less than 120 degrees apart but are symmetrically spaced from the remaining pin 22¹. Since the slots in the receptacle always bear the same relation to the optical unit, it is only necessary when the rebasing sleeve 21¹ is applied to the lamp, to similarly locate the respective pins 22¹ with respect to the filament 19 and thereby bring the flat side of the filament 19 in position to face the optical unit. 115

From the foregoing it will be observed 120 that this invention provides a lamp mounting for railway light signals, which permits lamps to be easily and quickly put in signals by ordinary and unskilled labor, 125 when required to replace those burnt out or otherwise rendered unfit for service, without requiring any special adjustment, and without likelihood of being wrongly placed by a careless workman. The rebasing scheme does not alter regular methods of 130

manufacturing lamps; but taking the lamps as made commercially, a positive and permanent adjustment is made of the filament with relation to its supporting elements, 5 namely, the sleeve 21 and pins 22, which not only locates the filament at the proper point when the lamp is put in a signal, but also disposes of the filament flatwise to the lens 2. The need for such adjustment and 10 the result is well illustrated by comparison of Figs. 1 and 5. In Fig. 1, the globe or bulb 25 of the incandescent lamp is substantially in alignment with the base 20 but the stem 26 is tilted toward the left, where- 15 as in Fig. 5 the stem 26 of the lamp is in alignment with the supplemental base 21¹, but the bulb 25 leans toward the right. It is to be understood that all the lamps will be rebased according to the same standard, 20 thereby permitting the lamps to be inter- changed and in each instance have their filaments 19 located at the same point and facing in the same direction.

The practical advantages of employing 25 such standardized lamps will be evident upon comparison with the old scheme of adjusting each signal whenever a new commercial lamp is put into service. In one case, the adjustment can be made in manu- 30 facture, with the aid of suitable tools and apparatus, assuring uniform and accurate results; whereas adjustments in the field are cumbersome and inaccurate, two workmen being required, one at the signal to make 35 the adjustment, and another at a distance to determine from the appearance of the signal when the proper adjustment has been made. Difficulty is also encountered in practice in communicating the necessary in- 40 formation from the man at a distance from the signal, often several thousand feet, to the man at the signal.

The structure of the rebasing sleeve and 45 its cooperating socket is effective in this invention to prevent displacement of the lamp by jar and vibration after once put in place, and also to make the manipulation of replacing lamps a practically fool proof per- 50 formance.

Having thus shown and described several 55 embodiments of the invention, it is to be understood that they do not exhaust the idea of means for carrying out this invention, but merely illustrate their nature and mode of operation.

What I claim, is:—

1. In a light signal, the combination with 60 an optical unit, a lamp socket of the bayonet type having the usual spring pressed contact plunger and three hook-shaped slots, said socket being fixed in the position where its axis and the plane of its slots have a predetermined space relation to the focal point of said optical unit, an incandescent lamp having a base with three radial pins 65

to fit in said socket, said lamp having a concentrated filament which is located in the same said predetermined relation to the axis of its base and the plane of its pins, whereby the filament of said lamp will come 70 at the focal point of the optical unit without adjustment whenever the lamp is inserted in the socket, the spring pressed plunger of the socket co-acting with said pins and slots to constitute a three-point 75 support which positions the lamp with the axis of its base in a definite angular relation to the axis of the socket irrespective of mechanical clearance between the base and the socket. 80

2. In a light signal, the combination with a lens, a lamp socket of the bayonet type having three slots and fixed in the position in which its axis and the plane of the closed ends of its slots bear a predetermined space 85 relation to the focal point of said lens, an incandescent lamp having a plain cylindrical base and concentrated filament assembled with the usual manufacturing irregularities in the location of the filament with respect to the base, a metallic sleeve to 90 fit said socket and having three radially projecting pins to engage in the slots of said socket, said sleeve being rigidly fixed to the base of the lamp and electrically connected thereto in that particular endwise and tilted position in which the filament of the lamp bears the same said predetermined relation to the axis of the sleeve and the plane of its pins, whereby the filament of 95 the lamp is positioned at the focal point of the lens whenever said sleeve is inserted in the socket irrespective of the location of the lamp filament relative to its base. 100

3. In a light signal, the combination with 105 a lens, a bayonet type socket having three hook-shaped slots therein, the distance between two of said slots being different than between either and the third slot, said socket having a plane of the closed ends of its slots 110 located a predetermined fixed distance from the focal point of said lens, the axis of said socket passing through said focal point, a metallic sleeve with radially projecting pins spaced the same as said slots and having an external diameter to make a close but detachable fit in said socket, an incandescent lamp having a convoluted concentrated filament and a plain cylindrical base assembled with the usual manufacturing in- 115 accuracies in the location of the filament with respect to the base, said lamp having its base soldered in said sleeve in that particular endwise and tilted position therein where the filament of the lamp is said fixed 125 distance from the plane of the pins of the sleeve and lies in the axis of the sleeve, and where the filament also has its ends disposed in a predetermined relation to said pins, whereby the filament of the lamp ir- 130

respective of the manufacturing inaccuracies in its location relative to its base comes at the focal point of the lens and faces the lens when the lamp is inserted in 5 said socket.

4. In a device of the character described for supporting incandescent lamps of commercial manufacture in bayonet type sockets such that the filaments of said lamps in each

10 instance have the same given space relation to said socket, the combination with an incandescent lamp having a convoluted concentrated filament and a plain cylindrical single contact base assembled with the usual 15 manufacturing inaccuracies, a metallic cylindrical sleeve having an outside diameter to make a close but separable fit in the socket with allowances for variations in manufacture, said sleeve having fixed outwardly projecting radial pins spaced to enter the slots in the socket, said sleeve having an inside diameter larger than the outside diameter of the lamp base sufficient to permit tilting of the lamp base in the 20 sleeve to the degree required to bring the filament in the axis of the sleeve irrespective of variations in the location of the filament with respect to the lamp base, said sleeve being soldered to the lamp base in the 25 that particular endwise and tilted relation where the filament lies in the axis of the sleeve with the ends of its filament in a line bearing a predetermined angular relation to the axes of said pins and where the filament is located a predetermined distance 30 from the plane of the pins of the sleeve.

5. A light source for use in any one of a large number of light projecting devices each having a lens and a bayonet type socket 40 fixed in position with its axis and slots in the same definite relation to the focal point of said lens, the combination with an incandescent lamp having two concentrated filaments connected in parallel to the same 45 lead-in wires and a plain cylindrical base assembled with the usual manufacturing irregularities in the location of the filaments with respect to the base, a metallic sleeve having three radially projecting pins, the 50 distance between two of said pins being different than the distance between either pin and the third pin, said sleeve being soldered on the base of the lamp in that particular tilted and endwise relation thereto in which 55 the filaments of the lamp has the same said definite relation to the axis of the sleeve and its pins as the axis of the socket and its slots has to the focal point of said lens, whereby 60 said lamp and sleeve can be inserted in any one of said sockets and will have its filament at the focal point of the associated lens.

6. In an optical device, the combination of a lens, a bayonet type socket provided 65 with slots unsymmetrically spaced and hav-

ing a predetermined spacial relation to the lens; and a lamp in said socket provided with similarly spaced pins, and a concentrated filament defining a plane through the axis of the socket; said pins and plane of 70 the filament having a predetermined relation, thereby establishing a definite and predetermined relation between said filament and pins.

7. A rebased incandescent lamp for use in 75 light signals for railroads and the like which require accurate location of the filaments of the lamps therein with respect to the bayonet type socket supporting the lamp, comprising a relatively short convoluted filament constituting a concentrated source of light and a plain cylindrical base assembled on the bulb of the lamp with the usual manufacturing inaccuracies in the location of the filament with respect to the 80 base, and means affording a cylindrical surface to fit in said socket and provided with three pins projecting radially with respect to the axis of the base, said means being rigidly attached and electrically connected 85 to said base in that particular relative position in which the filament is at a predetermined distance from the plane of said pins and is in the axis of said cylindrical surface, the ends of said filament also being in 90 a line bearing a predetermined angular relation to the axes of said pins.

8. A rebasing sleeve for attachment to 100 electric lamps of the usual commercial manufacture provided with the usual metallic bases so as to afford an auxiliary base by which the lamp may be supported in a socket with its filament in a definite relation thereto comprising; a metallic sleeve provided with a plurality of external radially projecting pins, the inside diameter of 105 said sleeve being larger than the outside diameter of the lamp base on which it is to be used, thereby permitting the lamp base to be tilted in the sleeve sufficiently to compensate for ordinary irregularities in filament location.

9. A rebasing sleeve for attachment to 110 electric lamps of the usual commercial manufacture having the usual metallic bases so as to afford an auxiliary base by which the lamp may be supported in a socket with its filament in a definite relation thereto comprising; a metallic sleeve provided with three external radially projecting pins, the 115 inside diameter of said sleeve being larger than the outside diameter of the lamp base on which it is to be used, thereby permitting the lamp base to be tilted in the sleeve sufficiently to compensate for ordinary irregularities in filament location.

10. A rebasing sleeve for attachment to 120 electric lamps of the usual commercial manufacture having the usual metallic bases so as to afford an auxiliary base by which 125

the lamp may be supported in a socket with its filament in a definite relation thereto comprising; a metallic sleeve having three external radially projecting unequally spaced pins, the inside diameter of said sleeve being larger than the outside diameter of the lamp base on which it is to be used, thereby permitting the lamp base to be tilted in the sleeve sufficiently to compensate for ordinary irregularities in filament location.

11. A rebasing sleeve for attachment to electric lamps of the usual commercial manufacture having the usual metallic bases so as to afford an auxiliary base by which the lamp may be supported in a socket with its filament in a definite relation thereto comprising; a metallic sleeve having radially extending pins and provided with spring tongues extending beyond the outer surface of said sleeve and between said pins, the inside diameter of said sleeve being larger than the outside diameter of the lamp base on which it is to be used, thereby permitting the lamp base to be tilted in the sleeve sufficiently to compensate for ordinary irregularities in filament location.

12. A rebasing sleeve for attachment to electric lamps of the usual commercial manufacture so as to afford an auxiliary base by which the lamp may be supported in a socket with its filament in a definite relation thereto comprising; a metallic slotted sleeve having radially extending pins and having the portion between adjacent slots bent outwardly, the inside diameter of said sleeve being larger than the outside diameter of the lamp base on which it is to be used, thereby permitting the lamp base to be tilted in the sleeve sufficiently to compensate for ordinary irregularities in filament location.

13. A rebased incandescent lamp for use in light signals for railroads and similar light projecting devices which require accurate location of the light source, comprising a plain cylindrical single contact base and two convoluted concentrated filaments connected to the same lead-in wires and assembled with the usual manufacturing irregularities in the location of the filaments with relation to the base, a metallic sleeve having three radially projecting pins and rigidly fixed and electrically connected to the base of the lamp in that particular adjusted position in which the filaments are a predetermined distance from the plane of

the three pins of said sleeve and in the axis of the sleeve, the ends of said filaments also being positioned in a line bearing a predetermined angular relation to the axes of the pins.

14. As an article of manufacture, an incandescent lamp having a concentrated filament and a plain cylindrical single contact base assembled with the usual manufacturing inaccuracies in the location of the filament with respect to the base, together with a supplemental metallic rebasing sleeve having three or more radially projecting pins and soldered to the base of the lamp in that particular endwise and tilted relation in which the filament, irrespective of its location relative to the lamp base, is positioned at a preselected distance from the plane of said pins and in a predetermined relation to the axis of said sleeve, said filament also having its ends positioned in a line bearing a predetermined angular relation to the axes of said pins.

15. A rebased incandescent lamp for use in light signals for railroads and similar light projecting units which require accurate location of the light source, comprising a plain cylindrical single contact base and a concentrated filament assembled with the usual manufacturing inaccuracies, a metallic sleeve having three radially extending pins unequally spaced around the periphery of the sleeve, said sleeve being soldered on the lamp base in that particular endwise or tilted relation in which the filament is located at a predetermined distance from the plane of said three pins and in a predetermined relation to the axis of the sleeve, the ends of said filament also lying in a line having a predetermined angular relation to the axes of said pins.

16. A rebasing sleeve for attachment to electric lamps of the usual commercial manufacture so as to afford an auxiliary base by which the lamp may be supported in a socket with its filament in a definite relation thereto comprising, a metallic sleeve provided with a plurality of unequally spaced pins, and tongues between said pins extending outwardly from said sleeve to form spring fingers for resiliently centering said sleeve in such socket.

In testimony whereof I hereto affix my signature.

EDMUND W. MOORE.
